TOY VEHICLE

Harry Kister, Philadelphia, Pa., assignor of one-half to William H. Eden, Philadelphia, Pa.

Application March 26, 1935, Serial No. 13,131

6 Claims. (Cl. 208—38)

This invention relates to express wagons, skooters, tricycles and similar toy vehicles adapted for manual propulsion; and particularly to those of the type employing treadmill apparatus for supplying the motive power to one or more of the supporting wheels of the device.

The present invention constitutes an improvement over the device shown in the applicant's prior Patent No. 1,533,651 dated April 4, 1925 10 wherein the treadmill consisted of an endless belt arranged in an inclined plane and operatively connected to the rear supporting wheels of the vehicle. In this type of device, due to various 15 conditions and to hard usage by children, the belt gives considerable trouble as a result of stretching, twisting and general deterioration, requiring frequent replacement and at the best failing to give entire satisfactory service.

The present invention relates particularly to an 20 improved form of treadmill structure, for a device of the type above noted, which will be of rugged durable construction requiring a minimum of attention and affording a useful life corresponding to that of the vehicle itself.

25 The construction and operation of the device forming the subject of the present invention will be fully disclosed hereinafter, reference being had to the accompanying drawings; of which:

Fig. 1 is a perspective view of a toy express 30 wagon equipped with a treadmill structure made in accordance with the principles of the present invention but showing the device adapted for normal use as a conventional coaster or shaft-drawn carrier;

35 Fig. 2 is a view similar to Fig. 1 but showing the device converted for propulsion by the contained treadmill;

Fig. 3 is a perspective view of a portion of the 40 vehicle body adapted for change of position in accordance with the form in which the device is to be used;

Fig. 4 is a detached perspective view of the 45 treadmill frame;

Fig. 5 is a sectional elevation taken on the line 50 5—5, Fig. 2;

Fig. 6 is a perspective view of a tricycle or 55 skooter equipped with the improved treadmill;

Fig. 7 is a sectional elevation taken on the line 60 7—7, Fig. 6; and

Fig. 8 is a sectional elevation taken on the line 65 8—8, Fig. 7.

In that form of vehicle illustrated in Figs. 1 and 2, the device comprises a toy express wagon 55 body 1 consisting of a bottom 2, a front or dash-

board 3, side boards 4 and 5 respectively, and a back or tail board 6.

The device is provided with a pair of front supporting wheels 7, 7. The wheels 7, 7 are rotatably mounted on a front axle 8 which is carried by a swivel frame 9. The frame 9 is arranged to turn about a vertical fifth-wheel pivot 10, under guidance of a draw-shaft or steering handle 11, in the usual manner.

The rear end of the vehicle is supported by 10 wheels 12 and 13 respectively, said wheels being rotatably mounted about the axis of a rear axle 14, said axle being mounted in brackets 15 and 16 which are disposed at opposite sides of the wagon body beneath the floor 2 thereof, said 15 brackets comprising substantially vertical posts 17 and 18 having feet 19 and 20 respectively by which one end of each bracket is secured to the wagon body.

Extending at an angle inclined to the plane of 20 the floor 2 of the vehicle and integrally connected to the lower ends of the posts 17 and 18 are side bars 21 and 22, the upper ends of which are provided with feet 23 and 24 respectively for securing the forward ends of said frame members 15 25 and 16 to the under side of the body 1, at a position forward of the center of the vehicle body.

Disposed between the inclined side bars 21 and 22 and extending transversely of the treadmill frame is a series of parallel laterally spaced driving rollers 25, 25, each of which is provided with oppositely axially extending trunnions 26 which are rotatably mounted in suitable bearings carried by or formed in the frame members 21 and 22 respectively, said rollers being in such closely 35 adjacent relation to each other that the foot of a user of the vehicle, under the weight of the person, will pass freely from one to the other of the rollers, down the inclined plane afforded by the rollers, thereby applying rotary motion to 40 each of the rollers as the foot passes across the rollers successively.

At one side of the vehicle, for example at the side adjacent the inclined frame member 21, each roller or its trunnion is provided with a gear 27 45 which is fixed to the trunnion or to the roller. Rotatably mounted on the frame member 21, intermediate each adjacently disposed pair of roller gears 27 is an intermediate gear 28 which intermeshes with the gears 27, 27 of the adjacently 50 disposed pair of rollers 25.

In the present instance, the gear 27 associated with the lowermost of the rollers 25 intermeshes with a gear 29 which, in this instance, is secured to the rear axle 14. In this instance, the rear 55

wheel 12 is also secured to the axle 14 while the wheel 13 is free to rotate on and relative to said axle.

The floor 2 of the wagon body 1 is provided with an elongated rectangular opening 30 which extends from the extreme rear edge of the floor 2 forwardly beyond the center of the wagon body, with the forward edge of the opening adjacent the forward feet 23 and 24 of the frame members 15 and 16 respectively.

The rectangular opening 30 is normally closed by a pair of trap doors 31 and 32 which are hinged together at the median line 33 and with the forward edge of the trap door 31 hinged to the floor 15 2, as illustrated at 34.

The opening 30 does not extend the full width of the floor 2 intermediate the side boards 4 and 5 whereby longitudinally extending steps or shelves 35 and 36 are provided at opposite sides respectively of the opening 30.

The trap doors 31 and 32 normally rest on side supports 35a which extend beyond the inner edges of the steps 35 and 36 respectively and support the trap doors with the upper sides thereof 25 flush with the top of the steps 35 and 36.

The back or tail board 6 is slidably mounted in vertical grooves 31, 37 formed in the side boards 4 and 5 respectively.

In order to convert the vehicle from the coaster or carrier form illustrated in Fig. 1 to the treadmill actuated form illustrated in Fig. 2, the back board 6 is removed and the trap doors 31 and 32 are folded upwardly one against the other about the axis of the hinge 33 and then forwardly about the axis of the hinge 34, until the trap doors come to rest upon the forward portion of the floor 2 immediately behind the front board 3, leaving the opening 30 in said floor clear and open for free operation of the treadmill rollers 25.

Mounted on the side boards 4 and 5 substantially at the forward edge of the opening 30 is an inverted U-shaped element 40, the side legs 41, 41 of which are pivoted at 42, 42 to said side boards 4 and 5 respectively. The legs or side members 41, 41 normally lie flatly on the shelves 35 and 36 of the wagon floor and the cross bar 43 normally lies in front of the back board 6, on top of the rear edge of the trap door 32.

When the vehicle is converted into the form shown in Fig. 2, the inverted U-shaped element 40 is swung about its pivots 42, 42 to a vertical position, with the forward edges of the uprights 41, 41 bearing against vertical blocks 44, 44 which are secured to the side boards 4 and 5 respectively.

Adjacent and parallel to the blocks 44, 44 the side boards 4 and 5 are provided with vertical grooves 45, 45 which are arranged to receive the opposite ends of the back board 6, behind the rear edges of the uprights 41, 41, whereby the U-shaped member 40 is maintained in the upright position illustrated in Fig. 2.

When the vehicle is converted to the form shown in Fig. 2, a youngster gripping the cross bar 43 with one hand and the handle 46 of the shaft 11 with the other hand, and by walking up the inclined plane afforded by the closely positioned rollers 25, 25 said rollers will be rotated in a counterclockwise direction as viewed in Fig. 2, and this rotation will be transmitted through the train of gears 27, 28 and 29 to the rear axle 14 of the vehicle and thence to the rear supporting and traction wheel 12 which is secured to said axle, thereby effecting forward motion of the vehicle.

When the vehicle attains the speed desired by the youngster, the youngster may coast under momentum by stepping up on to the steps 35 and 36, whereupon the rollers 25 will revolve freely under the attained momentum of the vehicle. 5

If the youngster desires to slow up the vehicle, one of the steps 35 or 36 is provided with a brake pedal 47 which may be either pivoted to or slidably mounted in the body of the vehicle and operatively connected to a brake shoe 48 which the 10 youngster may apply to the driving wheel 12 by stepping on the pedal 47.

Due to the rugged construction of the treadmill, as above described, little or no attention is required other than occasional lubrication of the 15 trunnions of the rollers and gears as no twisting or misalignment of the rollers or gears as comparable to the twisting or misalignment of the belt in the old type of device is encountered.

In that form of the device shown in Fig. 6, the 20 treadmill frame members 121 and 122 converge at their upper forward ends, beyond a transversely extending spreader 102, as indicated at 123 and 124 for the support of a centrally located bearing 110 in which is rotatably mounted a steering 25 post 111. The post 111 is provided at its upper end with handle bars 146 and at its lower end with a forked bearing 109 in which is rotatably mounted a guiding or steering wheel 107.

The rear ends of the side bars 121 and 122 are 30 mounted on the rear axle 114 and beyond said axle bend inwardly as indicated at 118 for supporting a rear coasting step 135.

The rear axle 114 is carried by the rear wheels 112, 113, one or the other of which may be secured to said axle while the second may revolve freely thereon. 35

The treadmill rollers 25, 25 are rotatably mounted in the side bar frame members 121 and 122 and geared together and to the rear axle 40 by the chain of gears 27, 28, 29 as noted above.

If desired, in both forms of the vehicle, the traction wheel 12 or 112, as the case may be, may be connectible with the rear axle by and through a one-direction or overrunning clutch illustrated 45 in Figs. 7 and 8, wherein the hub of the wheel is made in two concentric parts, 50 and 51. The inner part 50 is secured to the rear axle while the outer part is rotatably mounted on the inner part through laterally spaced ball bearings 52 and 53. 50

Intermediate the ball bearings 52 and 53, the inner part 50 is provided with one or more peripheral recesses 54 in each of which is freely mounted a grip roller 55.

When the inner part 50 is rotated in the direction of the arrow Fig. 8 the rollers, or balls, 55 become jammed in the angles formed by the inner circular surface 56 of the outer part 51 and the flat surfaces 57 of the recesses 54 in the inner part 50, whereby the two parts are rigidly locked together and drive the traction wheel 112. Thus, if the wheel 112 tends to run faster than the rollers 25 as the vehicle attains momentum the traction wheel 112 is automatically disconnected from the drive shaft 114 and operator may 60 then coast with one foot on the rear step 135 and the other braced against the then non-rotating rollers 25.

In each instance, the uppermost roller 25 is preferably freely rotatable in the treadmill frame 70 and is not geared to the other rollers. When stepped upon, the upper roller revolves freely and deposits the foot against the next succeeding roller with an impact which starts the treadmill operating more readily than if one merely de- 75

5 pended upon the inert weight of the operator tending to slide down the inclined plane afforded by the upper surfaces of the rollers to start the rollers revolving and for this reason the top roller in each instance may be referred to as a starting or impact roller.

10 Obviously, upon reading the above and viewing the annexed drawings, the detailed structure will be seen to be subject to numerous changes and modifications without deviating from the primary principles of the invention, in view of which only such limitations should be placed upon the appended claims as may be necessitated by the state 15 of the prior art.

15 I claim:

20 1. A toy vehicle comprising a plurality of supporting wheels, a series of driving rollers arranged in a common inclined plane in close laterally parallel relation and operatively connected together and to one of said supporting wheels, and an independently rotatable impact roller at the upper end of the inclined series.

25 2. A toy vehicle comprising a plurality of supporting wheels, a series of driving rollers operatively connected together and to one of said supporting wheels, and including an overrunning clutch between the roller series and the supporting wheel driven thereby.

30 3. A toy vehicle comprising a plurality of supporting wheels, a series of driving rollers, a gear on each roller, an intermediate gear between and intermeshing with the gears of each adjacently disposed pair of rollers, and means operatively connecting the gear train to one of said supporting 35 wheels.

4. A toy vehicle comprising a plurality of supporting wheels, a series of driving rollers, a gear on each roller, an intermediate gear between and intermeshing with the gears of each adjacently disposed pair of rollers, an axle for at least one 5 of said supporting wheels, a gear on said axle intermeshing with the train of gears operatively connecting said rollers, and means for operatively connecting said axle to said supporting wheel thereon.

10 5. A toy vehicle comprising a plurality of supporting wheels, a series of driving rollers, a gear on each roller, an intermediate gear between and intermeshing with the gears of each adjacently disposed pair of rollers, an axle for at least one 15 of said supporting wheels, a gear on said axle intermeshing with the train of gears operatively connecting said rollers, said supporting wheel comprising an inner hub portion secured to said 20 axle, an outer hub portion rotatable about said inner portion, and means for locking said inner and outer parts together by rotation of said inner part under power applied by rotation of said rollers in one direction.

25 6. A toy vehicle comprising a pair of laterally spaced side bars, a series of rollers having trunnions mounted for rotation in bearings carried by said side bars respectively, an axle rotatably mounted in said side bars, supporting wheels on and with one secured to said axle, and a train of gears operatively connecting said rollers and said 30 axle.

HARRY KISTER. 35
